UNITED STATES PATENT OFFICE.

EDWARD T. CURTISS, OF LOS ANGELES, CALIFORNIA.

TIMER.

1,380,316.

Specification of Letters Patent. Patented May 31, 1921.

Application filed March 24, 1919. Serial No. 284,787.

To all whom it may concern:

Be it known that I, EDWARD T. CURTISS, a citizen of the United States, residing at Los Angeles, in the county of Los Angeles and State of California, have invented new and useful Improvements in Timers, of which the following is a specification.

My invention relates to timers and consists of the novel features herein shown, described and claimed.

Figure 1 is a diametrical sectional detail on the irregular line 1—1 of Fig. 2.

Fig. 2 is an enlarged sectional detail on the line 2—2 of Fig. 1.

Fig. 3 is a diagrammatic view for tracing the circuit.

Fig. 4 is a fragmentary detail of the make and break lever and mounted as seen looking in the direction indicated by the arrow 20 4 in Fig. 2.

The cam shaft 1 extends through a bearing 2 in the engine case 3, and an annular bearing flange 4 extends outwardly from the face of the case 3. The timer case 5 has an annular rim 6 fitting rotatably upon the flange 4, an arm 7 extends from the case 5 and the mechanism for advancing and retarding the spark is to be connected to this arm. An annular insulating block 8 is placed against the inner face of the flat wall 9 of the case 5 and secured in place by screws 10, said block being concentric to the cam shaft 1, and the chamber 11 of the case being eccentric to the block. The contact plates 12, 13, 14 and 15 are secured to the inner face of the block 8 by screws 16, there being two screws in each plate. The plates 12, 13, 14 and 15 are separated by tangential gaps 17, so that the brush bearing 40 against the plates will pass gradually from one plate to the next across the gap.

The outer binding posts 18, 19, 20 and 21 are connected through the annular wall 22 of the case 5 all at one side and as near 45 together as may be. A wire 23 connects one of the screws 16 of the plate 12 to the binding post 18, a wire 24 connects the plate 13 to the post 19, a wire 25 connects the plate 14 to the post 20, and a wire 26 connects the plate 15 to the post 21, said wires being assembled in the chamber 11 at the large side of the chamber relative to the block 8.

The chamber 27 formed in the case 5 immediately in front of the flange 4 is concentric to the cam shaft 1, and a flange 28 is

formed from the partition 29 which separates the chamber 11 from the chamber 27 and extends upon an incline toward the engine case 3 and outwardly to form an annular pocket 29'. A hub 30 is fixed upon the end of the cam shaft 1 against the outer face of the bearing 2, a peripheral grooved disk 31 extends from the hub 30 outwardly as far as the pocket 29', a block of insulation 32 is fixed upon the hub 30 against the outer face of the disk 31, a tube 33 is fixed in the block 32, the inner end of the tube being closed by the block and the outer end being open, and a carbon brush 34 is slidingly mounted in the tube against the spring 35 in the bottom of the tube, and the tension of the spring is exerted to press the brush outwardly against the plates 12, 13, 14 and 15.

The block 32 is secured to the disk 31 by screws 36. A contacting plate 37 extends from the tube 33 and rests against the outer face of the block 32. A slot 38 is formed from the outer edge of the block 32. The make and break lever 39 is loosely mounted in the slot 38 and held pivotally in place by a screw 40. The screw 40 is approximately at the center of the lever 39. A pad 41 of insulation is fixed to the handle end 42 of the lever 39 to bear against the internal periphery 43 of the partition 29. A retractile coil spring 44 connects the live end 45 of the lever to the screw 46 tapped into the block 32, the tension of the spring being exerted to throw the handle end outwardly, so that the pad 41 will bear against the internal periphery 43. A contact point 47 is formed upon the extreme live end 45, said contact point being formed of suitable hard material, such as tungsten. A post 48 extends from the disk 31, a screw 49 is fixed through the post, and a contact point 50 is formed upon the point of the screw to engage the contact point 47, said point 50 being formed of suitable hard material, such as platinum or tungsten. Breaks 51, 52, 53 and 54 are formed in the internal periphery 43, said breaks being evenly spaced apart and of even lengths, and each of said breaks 55 and 56 having inclined entrances 55 and 56.

When the cam shaft 1 is rotating the pad 41 is bearing against the internal periphery 43 and the contact 47 is moved away from the contact 50 to break the electric circuit, and when the pad 41 reaches one of the breaks 51, 52, 53 or 54 the tension

of the spring 44 will throw the pad 41 into the break and snap the contact 47 against the contact 50 to close the circuit and make a spark. The spark may be advanced or retarded in the usual way through the arm 7.

The operation of the lever 39 makes and breaks the circuit independently of the position of the brush 34 upon the plates 12, 13, 14 and 15, consequently there will be no spark or make and break between the brush and the plates. The plates 12, 13, 14 and 15 simply serve as selecting means for taking the current through the desired one of the wires 23, 24, 25 and 26.

The wires 57, 58, 59 and 60 connect the binding posts 18, 19, 20 and 21 to the several spark plugs, said wires or lines running through the usual vibrator, coil box and source of energy, such as a magneto or a battery. The contact 50 is grounded through the screw 49, the post 48, the plate 31, and the cam shaft 1, and the spark plugs are grounded on the engine frame thus completing the circuits.

When the brush 34 is passing from one plate 12, 13, 14 and 15 to the other, the circuit is broken and there is no tendency for sparking or arcing between the brush and the plates. The circuits are controlled by a positive make and break between the points 47 and 50, and there is no rubbing contact between these points. The chamber contact between these points. The chamber 11 being eccentric to the chamber 27 and eccentric to the cam shaft 1 makes it possible to assemble the wires 23, 24, 25 and 26 in the chamber 11 with the wires all leading to one side and to assemble the binding posts 18, 19, 20 and 21 at one side of the timer and outside of the timer so as to get away from the fan belt and so as to avoid the necessity of distributing the lead wires 57, 58, 59 and 60 from radial points around the timer casing.

The oil which passes through the bearing 2 around the cam shaft 1 will be collected in the chamber 27 and will be deflected by the disk 31 to prevent the oil from passing to the timer mechanism, and any oil that is thrown outwardly by the disk 31 against the internal face of the rim 6 will be collected in the pocket 29 and discharged downwardly and may drain from the chamber 27 through the opening 61.

Various changes may be made without de-

parting from the spirit of my invention as claimed.

I claim:

1. A timer adapted to be mounted upon a cam shaft and including an eccentric chamber, binding posts assembled at the large side of the chamber, and moving contacts having conductors leading therefrom around said chamber to said binding posts. 60

2. In a timer in combination with a timing shaft mounted in a gear housing, a hub fixed upon the shaft having an insulating member, a brush flexibly carried in the insulating member, a casing rotatably mounted against the gear housing, an annular ring 70 positioned within the casing concentric to the timing shaft and opposed to the hub, a commutator ring fixed to the face of the annular ring in the casing and insulated from the casing and positioned to contact 75 with the brush carried by the hub, an annular flange disposed inwardly from the casing having notches equally spaced, a make and break arm pivotally mounted on the hub, an outer end of which carries a pad 80 of insulation and bears with resilient pressure against the notched flange of the casing and having on its inner end a contact point, a spring for holding the outer end of the lever resiliently against the notched flange, a second contact point carried by the hub in electric communication with the timing shaft positioned to be engaged by the point on the inner end of the arm, means electrically connecting the arm with the brush and means for connecting the annular commutator of the casing into the electric circuit of an ignition system. 85

3. A timer comprising a post mounted upon a timing shaft, a commutator ring 9 positioned to engage the brush, a make and break arm pivotally mounted on the shaft and insulated therefrom having a contact point at one end, a second point fixed to said shaft and electrically connected therewith, 1 adapted to contact with the point on the end of the arm, means for operating the arm to make and break the contact between the points adapted to be rotated to advance and retard their time of contact, and means for electrically connecting the arm to the brush.

In testimony whereof I have signed my name to this specification.

EDWARD T. CURTISS.
